FIG. 7

FIG. 8

FIG. 9

FIGURE 1 is a front right perspective view of a photographic camera showing our new design, with the front cover in closed condition;

FIG. 2 is a rear left perspective view thereof;

FIG. 3 is a top plan view thereof;

FIG. 4 is a bottom plan view thereof;

FIG. 5 is a view similar to FIGURE 1 but with the front cover removed;

FIG. 6 is a view similar to FIG. 5 but showing the viewfinder raised and the bellows extended;

FIG. 7 is a front elevational view thereof;

FIG. 8 is a side elevational view thereof; and FIG. 9 is a bottom plan view thereof.

We claim:

The ornamental design for a photographic camera or similar article, substantially as shown.
